EQUIPMENT FOR USE WITH CASKET- LOWERING DEVICES

John H. Lampe, Pocahontas, Iowa

Application October 13, 1939, Serial No. 299,367

2 Claims. (Cl. 193—42)

This invention relates broadly to casket-lowering devices, and more particularly to equipment for use in connection therewith to facilitate the placing of the casket or the box containing the casket on the lowering device; and the invention together with its objects and advantages will be best understood from a study of the following description taken in connection with the accompanying drawings wherein:

10 Figure 1 is a top plan view of a casket-lowering device having the equipment contemplated by this invention associated therewith.

Figure 2 is a fragmentary side elevational view of the assembly shown in Figure 1.

15 Figure 3 is a view similar to Fig. 2 but with a portion of the casket or rough box therefor shown for the purpose of illustrating the application of the invention.

Figure 4 is a perspective view of a bracket and 20 roller assembly forming part of the invention.

Figure 5 is a perspective view of a roller-equipped truck forming part of the invention.

Referring more in detail to the drawings it will 25 be seen that 5 indicates generally a more or less conventional and well-known type of casket-lowering device. In the present instance the device 5 is shown as consisting of a frame having longitudinal or side members 6 and end members 7. The side members 6 have windable thereon 30 straps 8 that are arranged to receive the cover plate 9 of the usual grave vault and which cover plate is generally placed first into the grave with the casket and the body, box-like in form, of the vault is then lowered into position onto the cover plate 9 as is believed to be well-known.

In accordance with the present invention the casket lowering device 5 is supported on a frame structure 10 that embodies side and end members joined together at the corners of the frame 10 35 by hollow corner posts 11 that are longitudinally adjustable for elevating the frame 10 and for levelling the same. In this connection it will be noted that the corner posts 16 of the casket raising and lowering device 5 set on the corner posts 11 of the frame 10 so that the raising and lowering device 5 will be raised or lowered and levelled in accordance with the raising and lowering or levelling of the frame 10.

40 Further in accordance with the present invention there is provided for disposition at one end of the casket-lowering device 5 a bracket indicated generally by the reference numeral 12.

The bracket 12 comprises a pair of spaced posts 45 51 connected together intermediate their ends by

a spacer bar 14 that in the present instance is shown integral with the posts 13.

The posts 13 at the upper ends thereof are provided with bearings 15 in which are journaled the pintles of a roller 16. The roller 16 may consist of a wooden core with a brass covering or surface or may be in the nature of a rubber roller as found desirable.

For mounting the bracket 12 in position the standards or posts 13 of the bracket adjacent the upper ends thereof are provided with integral hooks 17 that engage over an end rail 7 of the casket-lowering device 5 as clearly suggested in Fig. 3.

The lower ends of the legs or posts 13 are slotted 51 as at 18 to accommodate nut-equipped bolts 19 through the medium of which substantially inverted U-shaped clips 20 are adjustably secured to the legs or standards 13.

As shown in Fig. 3 the clips 20 engage over the 20 adjacent end rail 10a of the levelling frame 10. Thus through the medium of the hooks 17 and the clips 20 the roller-equipped bracket 12 is secured in position at one end of the casket-lowering device 5; and by the adjustability of the clips 20 25 on the legs or standards 13 said bracket 12 can be used in connection with substantially any known type of casket-lowering device.

Also in accordance with the present invention there is provided, as clearly shown in Fig. 5, a 30 truck indicated generally by the reference numeral 21.

The truck 21 comprises a substantially rectangular frame 24 formed of iron or other suitable material provided at its opposite ends with bearings 22 in which are journaled the pintles of an elongated roller 23 that is of a length substantially equal to the length of the frame 24 of the carriage 21.

Also at the corners thereof the frame 24 of the 40 carriage is provided with upstanding prongs 25 that will imbed themselves in the bottom of the casket or the rough box in which the casket is usually placed, and as shown in Fig. 3, when an end portion of such casket or box is placed thereon.

The utility and advantages of the invention will be apparent from the following:

In using the apparatus of the invention the frame 10 is of course placed in position after which the casket-lowering device 5 is mounted on the frame as shown. The frame 10 and casket-lowering device 5 is then levelled as found desirable and the cover of the grave vault 9 is then 55

properly positioned on the casket-raising and lowering device 5.

The bracket 12 is then mounted at one end of the device 5 and frame 10 as hereinbefore explained and the carriage or truck 21 then placed on the vault covering 9 a reasonable distance from the bracket 12, as for example about two feet from said bracket.

One end of the casket or the rough box containing the same is placed on the roller 16 mounted on the bracket 12 and the casket then pushed forward until the forward end thereof is slightly past or beyond the truck 21 when said end of the casket or box containing the same is then lowered down into a position for rest on the frame 24 of the truck or carriage 21 as shown in Fig. 3. The prongs 25 will then bite into the bottom of the casket or box 26 containing the casket, as the case may be, and further movement of the casket or box 26 longitudinally will of course result in the carriage or truck 21 moving therewith so that this movement of the casket or box containing the same can be accomplished without much effort and in this way the casket or box 26 brought into a proper position of rest on the vault cover 9. When this object has been completed then the device 5 is operated for lowering the casket or box 26 into the grave. In connection with the above it will of course be understood that just immediately prior to the actual lowering of the casket the carriage 21 will be removed from beneath the casket or box 26.

It is thought that a clear understanding of the construction, operation and advantages of an invention of this character will be had without a more detailed description.

Having thus described the invention what is claimed as new is:

1. A device for use in connection with a casket-lowering device, said device including a bracket embodying a pair of standards, a spreader bar connecting said standards, a roller supported between the standards at the upper ends of the latter, support-engaging hooks on the standards adjacent the upper ends thereof, and additional support-engaging clips adjustably mounted on said standards at the lower ends of the latter. 15

2. A device for use in connection with a casket-lowering device, said device including a bracket embodying a pair of standards, a spreader bar connecting said standards, a roller supported between the standards at the upper ends of the latter, support-engaging hooks on the standards adjacent the upper ends thereof, and additional support-engaging clips adjustably mounted on said standards at the lower ends of the latter, for use in combination with a casket-receiving truck 20 embodying a rectangular frame equipped with bearings at the opposite ends thereof and a roller having pintles journaled in said bearings. 25
